UNITED STATES PATENT OFFICE

125,003

DESIGN FOR A PORTABLE LAMP

Carroll J. Rogers, Chicago, Ill.

Application September 9, 1940, Serial No. 94,905

Term of patent 3½ years

To all whom it may concern:

Be it known that I, Carroll J. Rogers, a citizen of the United States and residing in the city of Chicago, in the county of Cook and State of Illinois, have invented a new, original, and ornamental Design for a Portable Lamp, of which the following is the specification, reference being had to the accompanying drawing, forming a part thereof.

On the drawing:

Fig. 1 is a front elevational view of a portable lamp showing my new design.

Fig. 2 is a top plan view thereof.

Fig. 3 is an end elevational view showing my portable lamp looking at the right-hand end of Fig. 1.

I claim:

The ornamental design for a portable lamp, substantially as shown.

CARROLL J. ROGERS.
